UNITED STATES PATENT OFFICE.

GEORGE W. LANCASTER, OF RICHMOND, VIRGINIA, ASSIGNOR TO TELLER PROTECTOR COMPANY, INC., OF RICHMOND, VIRGINIA, A CORPORATION OF DELAWARE.

SILENT ELECTRIC SIGNAL FOR BANKS.

1,401,087.

Specification of Letters Patent. Patented Dec. 20, 1921.

Application filed November 23, 1916. Serial No. 132,980.

To all whom it may concern:

Be it known that I, GEORGE W. LANCASTER, a citizen of the United States, residing at Richmond, in the county of Henrico and 5 State of Virginia, have invented certain new and useful Improvements in Silent Electric Signals for Banks; and I do hereby declare the following to be a full, clear, and exact description of the invention, such as will 10 enable others skilled in the art to which it appertains to make and use the same.

The invention relates to a silent electric signal for banks.

The object of the present invention is to 15 provide a simple, practical and efficient silent electric signal for banks designed for use of paying tellers or a similar official and the bookkeeper or other accountant and adapted to enable the paying teller to transmit to the bookkeeper the name of the depositor without leaving the cage and capable also of providing means for enabling the bookkeeper to indicate to the paying teller the amount of the balance of the depositor 20 25 without the depositor having any knowledge of the operation of the signal whereby the safety of financial institutions will be materially increased without subjecting a depositor to humiliation or annoyance caused by the paying teller or similar official leaving his cage or position at the window to look up an account.

A further object of the invention is to 30 provide a silent signal of this character 35 adapted to enable various other information to be transmitted from one portion of the institution to another for notifying the bank employees of the presence of a burglar or the like.

With these and other objects in view, the 40 invention consists in the construction and novel combination of parts hereinafter fully described, illustrated in the accompanying drawings, and pointed out in the claims 45 hereto appended; it being understood that various changes in the form, proportion, size and minor details of construction, within the scope of the claims, may be resorted to without departing from the spirit or 50 sacrificing any of the advantages of the invention.

In the drawings—

Figure 1 is a vertical sectional view of an instrument designed for the use of a paying

teller and constructed in accordance with 55 this invention.

Fig. 2 is a vertical sectional view on the line 2—2 of Fig. 1.

Fig. 3 is a horizontal sectional view on the line 3—3 of Fig. 1.

Fig. 4 is a vertical sectional view of the bookkeeper's instrument illustrating the arrangement of the lamps and characters operated by the paying teller's instrument.

Fig. 5 is a horizontal sectional view of 65 the bookkeeper's instrument illustrating the arrangement of the keys for signaling the paying teller.

Fig. 6 is a diagrammatic view illustrating the arrangement of the circuit controlled by 70 the keys of the paying teller.

Fig. 7 is a similar diagrammatic view illustrating the arrangement of the circuit controlled by the keys of the bookkeeper.

Like numerals of reference designate corresponding parts in the several figures of 75 the drawings.

In the accompanying drawings in which is illustrated the preferred embodiment of the invention, 1 designates a paying teller's 80 instrument designed to be installed within the cage of a paying teller or other official of a bank or similar financial institution or the like, and comprising a support provided with a vertical back 2 and a horizontal base 85 3. The back 2 supports a series of lamps 4 which are connected with and adapted to be caused to glow by a bookkeeper's instrument 5. The lamps 4 which are ordinary electric lamps are preferably arranged in transparent or semi-transparent shells 6 bearing suitable characters 7 which as illustrated in Fig. 2 of the drawings consist of the numerals 0 to 9, a dollar sign, a period or decimal point and a colored signal 8. Any number of the color signals may be of course employed for transmitting various information.

The base of the paying teller's instrument 1, is equipped with a set of movable contacts 9 and fixed contacts 10 arranged in 100 the path of the movable contacts and adapted to coact therewith for closing a signal circuit and lighting a lamp corresponding to the contact 9 operated. The movable contact 9 is preferably in the form of a key pivoted 105 at 11 and provided with a suitable head 12 bearing a character such as a letter. When the head 12 is pressed upon by the finger,

the movable contact 9 will be carried into engagement with the relatively fixed contacts 10 and the circuit will be closed as will be readily understood.

5 The bookkeeper's instrument 5 comprises a support consisting of a horizontal base 13 and a vertical back 14. The supports of the paying teller's instrument and the bookkeeper's instrument may of course be of any 10 other desired form but the form shown is a convenient form and will conceal the signals sufficiently for the purpose intended.

The back 14 of the bookkeeper's instrument is equipped with a series of lamps 15 which are covered by transparent shells 16

constructed similar to the shells heretofore described and provided with letters 17 or other characters and certain of the shells are colored to form signals 18 but the signals 20 may be distinguished in any other manner from the characters of the back 14 of the bookkeeper's instrument. The characters and the signals of the bookkeeper's instrument correspond with the characters

25 of the movable contacts 9 of the base of the paying teller's instrument and when any one of the characters of the paying teller's instrument is depressed for closing the circuit between it and the bookkeeper's instrument the corresponding lamp of the bookkeeper's instrument will be caused to glow and it will be clear that the paying teller may quickly spell the name of any depositor and the signals formed by the colored shells

35 will enable the bookkeeper and cashier to indicate the presence of each other so that the cashier or paying teller or other official will not attempt to spell the name of a depositor or other person until the presence 40 of the bookkeeper is assured. The base of the bookkeeper's instrument is equipped with movable contacts 19 pivoted at 20 and arranged above to coöperate with relatively fixed contacts 21. The movable contacts of

45 the bookkeeper's instrument are provided with heads 22 bearing figures 23 or other characters such as a dollar sign, period and color signals and when one of the movable contacts of the bookkeeper's instrument is

50 depressed, the corresponding lamps of the paying teller's instrument will be caused to glow and the amount of a depositor's balance or the like may be readily and instantly transmitted to the paying teller or other 55 bank official without the customer or depositor becoming aware that the paying teller has consulted the bookkeeper.

The circuits of the fixed and movable contacts of the paying teller's instrument and 60 the lamps of the bookkeeper's instrument is arranged as illustrated in Fig. 6 of the accompanying drawings.

The movable contacts 9 of the paying teller's instrument are all connected by 65 branch wires 24 with one of the terminals

of the lamps of the bookkeeper's instrument and the fixed contacts 10 of the paying teller's instrument are all connected with a single wire 25 connected with one pole of a battery 26 or other suitable source of current supply. The other pole of the battery 26 is connected by a wire 27 having branch wires 28 connected with the other terminals of the lamps of the bookkeeper's instrument. By this arrangement the circuits will be closed when any one of the movable contacts of the paying teller's instrument is depressed. The wires may be arranged in any desired manner and the parts will be suitably insulated.

The circuit of the instrument of the bookkeeper is illustrated in Fig. 7 in which the movable contacts 19 of the said bookkeeper's instrument are connected by wires 29 with one of the terminals of the lamps of the paying teller's instrument and the fixed contacts 21 of the bookkeeper's instrument are connected by a single wire 30 with one of the poles of a battery 31 which in practice may be the same battery as the battery 26 or a separate source of current supply. The other terminals of the lamps of the paying teller's instrument are connected with branch wires 32 of a wire 33 which is connected with the other pole of the battery 31. By this construction, the corresponding lamp of the paying teller's instrument will be caused to glow when one of the keys of the bookkeeper's instrument is depressed.

While the silent signal of the present invention is described with reference to banks and similar financial institutions, it will be apparent that it may be employed wherever a signaling system of this character will be found advantageous or desirable.

The keys of the circuit closers are preferably supported in an elevated open position by coiled springs 34 and 35 but various other circuit closing means may of course be provided and while the devices of each instrument are preferably mounted on a single support they may be arranged in any other desired manner.

What is claimed is:—

1. In a signal system for banks, in combination, a station having a combined transmitter and annunciator comprising a base, a substantially vertical opaque upright on said base, circuit closers mounted on the base each having associated therewith one of the letters of the alphabet and signal elements mounted on the upright on the side facing the circuit closers each having associated therewith one of a group of indicia including numerals and characters to represent an amount of money, a second station having a second annunciator including signal elements each having associated therewith one of the letters of the alphabet and a second transmitter comprising a plurality 115 of

of circuit closers each having associated therewith one of a group of indicia including numerals and characters, and electric circuits connecting the circuit closers of the 5 first station with the corresponding signal elements of the second station and the circuit closers of the second station with the corresponding signal elements of the first station respectively.

10 2. The structure of claim 1 with said sig-

nal elements of said first and second stations as lamps, shells disposed over said lamps and having said letters, numerals and characters delineated thereon.

In testimony whereof I affix my signature 15 in presence of two witnesses.

GEORGE W. LANCASTER.
